US00D375520S

United States Patent

[19]

Koch et al.**Patent Number: Des. 375,520****Date of Patent: **Nov. 12, 1996**

[54] **LABEL PRINTER SUCH AS FOR PRINTING STICK-ON LABELS, BARCODE LABELS, AND GUMMED LABELS, SUCH AS FOR APPLICATION TO RETAIL GOODS**

[75] Inventors: **Ulf Koch; Dirk Umbach**, both of Eberbach; **Arno Körner**, Utting, all of Germany

[73] Assignee: **Esselte Meto International GmbH**, Heppenheim, Germany

[**] Term: **14 Years**

[21] Appl. No.: **22,172**

[22] Filed: **Apr. 15, 1994**

[30] Foreign Application Priority Data

Oct. 15, 1993 [DE] Germany ..... M 93 07 967.2

[57] **CLAIM**

The ornamental design for a label printer such as for printing stick-on labels, barcode labels, and gummed labels, such as for application to retail goods, as shown and described.

DESCRIPTION

FIG. 1 is a perspective view of a first embodiment of a label printer such as for printing stick-on labels, barcode labels, and gummed labels, such as for application to retail goods showing our new design;

FIG. 2 is one side view of the first embodiment;

FIG. 3 is the other side view of the first embodiment;

FIG. 4 is a top view of the first embodiment;

FIG. 5 is a bottom view of the first embodiment;

FIG. 6 is a front view of the first embodiment;

FIG. 7 is a rear view of the first embodiment;

FIG. 8 is a perspective view of a second embodiment;

FIG. 9 is one side view of the second embodiment;

FIG. 10 is the other side view of the second embodiment;

FIG. 11 is a top view of the second embodiment;

FIG. 12 is a bottom view of the second embodiment;

FIG. 13 is a front view of the second embodiment;

FIG. 14 is a rear view of the second embodiment;

FIG. 15 is a perspective view of a third embodiment;

FIG. 16 is one side view of the third embodiment;

FIG. 17 is the other side view of the third embodiment;

FIG. 18 is a top view of the third embodiment;

FIG. 19 is a bottom view of the third embodiment;

FIG. 20 is a front view of the third embodiment;

FIG. 21 is a rear view of the third embodiment;

FIG. 22 is a perspective view of a fourth embodiment;

FIG. 23 is one side view of the fourth embodiment;

FIG. 24 is the other side view of the fourth embodiment;

FIG. 25 is a top view of the fourth embodiment;

FIG. 26 is a bottom view of the fourth embodiment;

FIG. 27 is a front view of the fourth embodiment;

FIG. 28 is a rear view of the fourth embodiment;

FIG. 29 is a perspective view of a fifth embodiment;

FIG. 30 is one side view of the fifth embodiment;

FIG. 31 is the other side view of the fifth embodiment;

FIG. 32 is a top view of the fifth embodiment;
FIG. 33 is a bottom view of the fifth embodiment;
FIG. 34 is a front view of the fifth embodiment;
FIG. 35 is a rear view of the fifth embodiment;
FIG. 36 is a perspective view of a sixth embodiment;
FIG. 37 is one side view of the sixth embodiment;
FIG. 38 is the other side view of the sixth embodiment;
FIG. 39 is a top view of the sixth embodiment;
FIG. 40 is a bottom view of the sixth embodiment;
FIG. 41 is a front view of the sixth embodiment;
FIG. 42 is a rear view of the sixth embodiment;
FIG. 43 is a perspective view of a seventh embodiment;
FIG. 44 is one side view of the seventh embodiment;
FIG. 45 is the other side view of the seventh embodiment;
FIG. 46 is a top view of the seventh embodiment;
FIG. 47 is a bottom view of the seventh embodiment;
FIG. 48 is a front view of the seventh embodiment;
FIG. 49 is a rear view of the seventh embodiment;
FIG. 50 is a perspective view of a eighth embodiment;
FIG. 51 is one side view of the eighth embodiment;
FIG. 52 is the other side view of the eighth embodiment;
FIG. 53 is a top view of the eighth embodiment;
FIG. 54 is a bottom view of the eighth embodiment;
FIG. 55 is a front view of the eighth embodiment;
FIG. 56 is a rear view of the eighth embodiment;
FIG. 57 is a perspective view of a ninth embodiment;
FIG. 58 is one side view of the ninth embodiment;
FIG. 59 is the other side view of the ninth embodiment;
FIG. 60 is a top view of the ninth embodiment;
FIG. 61 is a bottom view of the ninth embodiment;
FIG. 62 is a front view of the ninth embodiment;
FIG. 63 is a rear view of the ninth embodiment;
FIG. 64 is a perspective view of a tenth embodiment;
FIG. 65 is one side view of the tenth embodiment;
FIG. 66 is the other side view of the tenth embodiment;
FIG. 67 is a top view of the tenth embodiment;
FIG. 68 is a bottom view of the tenth embodiment;
FIG. 69 is a front view of the tenth embodiment;
FIG. 70 is a rear view of the tenth embodiment;
FIG. 71 is a perspective view of a eleventh embodiment;
FIG. 72 is one side view of the eleventh embodiment;
FIG. 73 is the other side view of the eleventh embodiment;
FIG. 74 is a top view of the eleventh embodiment;
FIG. 75 is a bottom view of the eleventh embodiment;
FIG. 76 is a front view of the eleventh embodiment;
FIG. 77 is a rear view of the eleventh embodiment;
FIG. 78 is a perspective view of a twelfth embodiment;
FIG. 79 is one side view of the twelfth embodiment;
FIG. 80 is the other side view of the twelfth embodiment;
FIG. 81 is a top view of the twelfth embodiment;
FIG. 82 is a bottom view of the twelfth embodiment;
FIG. 83 is a front view of the twelfth embodiment;
FIG. 84 is a rear view of the twelfth embodiment;
FIG. 85 is a perspective view of a thirteenth embodiment;
FIG. 86 is one side view of the thirteenth embodiment;
FIG. 87 is the other side view of the thirteenth embodiment;
FIG. 88 is a top view of the thirteenth embodiment;
FIG. 89 is a bottom view of the thirteenth embodiment;
FIG. 90 is a front view of the thirteenth embodiment;
FIG. 91 is a rear view of the thirteenth embodiment;
FIG. 92 is a perspective view of a fourteenth embodiment;
FIG. 93 is one side view of the fourteenth embodiment;
FIG. 94 is the other side view of the fourteenth embodiment;
FIG. 95 is a top view of the fourteenth embodiment;

FIG. 96 is a bottom view of the fourteenth embodiment;
FIG. 97 is a front view of the fourteenth embodiment;
FIG. 98 is a rear view of the fourteenth embodiment;
FIG. 99 is a perspective view of a fifteenth embodiment;
FIG. 100 is one side view of the fifteenth embodiment;
FIG. 101 is the other side view of the fifteenth embodiment;
FIG. 102 is a top view of the fifteenth embodiment;
FIG. 103 is a bottom view of the fifteenth embodiment;
FIG. 104 is a front view of the fifteenth embodiment;
FIG. 105 is a rear view of the fifteenth embodiment;
FIG. 106 is a perspective view of a sixteenth embodiment;
FIG. 107 is one side view of the sixteenth embodiment;
FIG. 108 is the other side view of the sixteenth embodiment;
FIG. 109 is a top view of the sixteenth embodiment;
FIG. 110 is a bottom view of the sixteenth embodiment;
FIG. 111 is a front view of the sixteenth embodiment;
FIG. 112 is a rear view of the sixteenth embodiment;
FIG. 113 is a perspective view of a seventeenth embodiment;
FIG. 114 is one side view of the seventeenth embodiment;
FIG. 115 is the other side view of the seventeenth embodiment;
FIG. 116 is a top view of the seventeenth embodiment;
FIG. 117 is a bottom view of the seventeenth embodiment;
FIG. 118 is a front view of the seventeenth embodiment;
FIG. 119 is a rear view of the seventeenth embodiment;
FIG. 120 is a perspective view of a eighteenth embodiment;
FIG. 121 is one side view of the eighteenth embodiment;
FIG. 122 is the other side view of the eighteenth embodiment;
FIG. 123 is a top view of the eighteenth embodiment;
FIG. 124 is a bottom view of the eighteenth embodiment;
FIG. 125 is a front view of the eighteenth embodiment;
FIG. 126 is a rear view of the eighteenth embodiment;
FIG. 127 is a perspective view of a nineteenth embodiment;
FIG. 128 is one side view of the nineteenth embodiment;
FIG. 129 is the other side view of the nineteenth embodiment;
FIG. 130 is a top view of the nineteenth embodiment;
FIG. 131 is a bottom view of the nineteenth embodiment;
FIG. 132 is a front view of the nineteenth embodiment;
FIG. 133 is a rear view of the nineteenth embodiment;
FIG. 134 is a perspective view of a twentieth embodiment;
FIG. 135 is one side view of the twentieth embodiment;
FIG. 136 is the other side view of the twentieth embodiment;
FIG. 137 is a top view of the twentieth embodiment;
FIG. 138 is a bottom view of the twentieth embodiment;
FIG. 139 is a front view of the twentieth embodiment;
FIG. 140 is a rear view of the twentieth embodiment;
FIG. 141 is a perspective view of a twenty-first embodiment;
FIG. 142 is one side view of the twenty-first embodiment;
FIG. 143 is the other side view of the twenty-first embodiment;
FIG. 144 is a top view of the twenty-first embodiment;
FIG. 145 is a bottom view of the twenty-first embodiment;
FIG. 146 is a front view of the twenty-first embodiment;
FIG. 147 is a rear view of the twenty-first embodiment;
FIG. 148 is a perspective view of a twenty-second embodiment;
FIG. 149 is one side view of the twenty-second embodiment;
FIG. 150 is the other side view of the twenty-second embodiment;
FIG. 151 is a top view of the twenty-second embodiment;
FIG. 152 is a bottom view of the twenty-second embodiment;

FIG. 153 is a front view of the twenty-second embodiment;
FIG. 154 is a rear view of the twenty-second embodiment;
FIG. 155 is a perspective view of a twenty-third embodiment;
FIG. 156 is one side view of the twenty-third embodiment;
FIG. 157 is the other side view of the twenty-third embodiment;
FIG. 158 is a top view of the twenty-third embodiment;
FIG. 159 is a bottom view of the twenty-third embodiment;
FIG. 160 is a front view of the twenty-third embodiment;
FIG. 161 is a rear view of the twenty-third embodiment;
FIG. 162 is a perspective view of a twenty-fourth embodiment;
FIG. 163 is one side view of the twenty-fourth embodiment;
FIG. 164 is the other side view of the twenty-fourth embodiment;
FIG. 165 is a top view of the twenty-fourth embodiment;
FIG. 166 is a bottom view of the twenty-fourth embodiment;
FIG. 167 is a front view of the twenty-fourth embodiment;
FIG. 168 is a rear view of the twenty-fourth embodiment;
FIG. 169 is a perspective view of a twenty-fifth embodiment;
FIG. 170 is one side view of the twenty-fifth embodiment;
FIG. 171 is the other side view of the twenty-fifth embodiment;
FIG. 172 is a top view of the twenty-fifth embodiment;
FIG. 173 is a bottom view of the twenty-fifth embodiment;
FIG. 174 is a front view of the twenty-fifth embodiment;
FIG. 175 is a rear view of the twenty-fifth embodiment;
FIG. 176 is a perspective view of a twenty-sixth embodiment;
FIG. 177 is one side view of the twenty-sixth embodiment;
FIG. 178 is the other side view of the twenty-sixth embodiment;
FIG. 179 is a top view of the twenty-sixth embodiment;
FIG. 180 is a bottom view of the twenty-sixth embodiment;
FIG. 181 is a front view of the twenty-sixth embodiment;
FIG. 182 is a rear view of the twenty-sixth embodiment;
FIG. 183 is a perspective view of a twenty-seventh embodiment;
FIG. 184 is one side view of the twenty-seventh embodiment;
FIG. 185 is the other side view of the twenty-seventh embodiment;
FIG. 186 is a top view of the twenty-seventh embodiment;
FIG. 187 is a bottom view of the twenty-seventh embodiment;
FIG. 188 is a front view of the twenty-seventh embodiment;
FIG. 189 is a rear view of the twenty-seventh embodiment;
FIG. 190 is a perspective view of a twenty-eighth embodiment;
FIG. 191 is one side view of the twenty-eighth embodiment;
FIG. 192 is the other side view of the twenty-eighth embodiment;
FIG. 193 is a top view of the twenty-eighth embodiment;
FIG. 194 is a bottom view of the twenty-eighth embodiment;
FIG. 195 is a front view of the twenty-eighth embodiment;
FIG. 196 is a rear view of the twenty-eighth embodiment;
FIG. 197 is a perspective view of a twenty-ninth embodiment;
FIG. 198 is one side view of the twenty-ninth embodiment;
FIG. 199 is the other side view of the twenty-ninth embodiment;

FIG. 200 is a top view of the twenty-ninth embodiment;
FIG. 201 is a bottom view of the twenty-ninth embodiment;
FIG. 202 is a front view of the twenty-ninth embodiment;
FIG. 203 is a rear view of the twenty-ninth embodiment;
FIG. 204 is a perspective view of a thirtieth embodiment;
FIG. 205 is one side view of the thirtieth embodiment;
FIG. 206 is the other side view of the thirtieth embodiment;
FIG. 207 is a top view of the thirtieth embodiment;
FIG. 208 is a bottom view of the thirtieth embodiment;
FIG. 209 is a front view of the thirtieth embodiment;
FIG. 210 is a rear view of the thirtieth embodiment;
FIG. 211 is a perspective view of a thirty-first embodiment;
FIG. 212 is one side view of the thirty-first embodiment;
FIG. 213 is the other side view of the thirty-first embodiment;
FIG. 214 is a top view of the thirty-first embodiment;
FIG. 215 is a bottom view of the thirty-first embodiment;
FIG. 216 is a front view of the thirty-first embodiment;
FIG. 217 is a rear view of the thirty-first embodiment;
FIG. 218 is a perspective view of a thirty-second embodiment;
FIG. 219 is one side view of the thirty-second embodiment;
FIG. 220 is the other side view of the thirty-second embodiment;
FIG. 221 is a top view of the thirty-second embodiment;
FIG. 222 is a bottom view of the thirty-second embodiment;
FIG. 223 is a front view of the thirty-second embodiment;
FIG. 224 is a rear view of the thirty-second embodiment;
FIG. 225 is a perspective view of a thirty-third embodiment;
FIG. 226 is one side view of the thirty-third embodiment;
FIG. 227 is the other side view of the thirty-third embodiment;
FIG. 228 is a top view of the thirty-third embodiment;
FIG. 229 is a bottom view of the thirty-third embodiment;
FIG. 230 is a front view of the thirty-third embodiment;
FIG. 231 is a rear view of the thirty-third embodiment;
FIG. 232 is a perspective view of a thirty-fourth embodiment;
FIG. 233 is one side view of the thirty-fourth embodiment;
FIG. 234 is the other side view of the thirty-fourth embodiment;
FIG. 235 is a top view of the thirty-fourth embodiment;
FIG. 236 is a bottom view of the thirty-fourth embodiment;
FIG. 237 is a front view of the thirty-fourth embodiment;
FIG. 238 is a rear view of the thirty-fourth embodiment;
FIG. 239 is a perspective view of a thirty-fifth embodiment;
FIG. 240 is one side view of the thirty-fifth embodiment;
FIG. 241 is the other side view of the thirty-fifth embodiment;
FIG. 242 is a top view of the thirty-fifth embodiment;
FIG. 243 is a bottom view of the thirty-fifth embodiment;
FIG. 244 is a front view of the thirty-fifth embodiment;
FIG. 245 is a rear view of the thirty-fifth embodiment;
FIG. 246 is a perspective view of a thirty-sixth embodiment;
FIG. 247 is one side view of the thirty-sixth embodiment;
FIG. 248 is the other side view of the thirty-sixth embodiment;
FIG. 249 is a top view of the thirty-sixth embodiment;
FIG. 250 is a bottom view of the thirty-sixth embodiment;
FIG. 251 is a front view of the thirty-sixth embodiment; and,
FIG. 252 is a rear view of the thirty-sixth embodiment.
